Primary Examiner — Karen S Acker(74) *Attorney, Agent, or Firm* — Burr & Forman LLP(57) **CLAIM**

The ornamental design for a nonwoven fabric, as shown and described.

DESCRIPTION

FIG. 1 is a front perspective view of a nonwoven fabric, embodying the new design;

FIG. 2 is a front view of the nonwoven fabric of FIG. 1; FIG. 3 is a right-side view of the nonwoven fabric of FIG. 1;

FIG. 4 is a top-side view of the nonwoven fabric of FIG. 1; and,

FIG. 5 is a bottom-side view of the nonwoven fabric of FIG. 1.

The broken lines and unshaded side surfaces adjacent to solid lines depict portions of the nonwoven fabric that form no part of the claimed design.
